UNITED STATES PATENT OFFICE.

JOHN FRIEND LODGE, OF PHILADELPHIA, PENNSYLVANIA.

DEVICE FOR REMOVING SNARLS, KINKS, SLACKS, &c., FROM YARN AND THREAD.

988,362.

Specification of Letters Patent. Patented Apr. 4, 1911.

Application filed September 16, 1909. Serial No. 517,964.

To all whom it may concern:

Be it known that I, JOHN FRIEND LODGE, a citizen of the United States, residing in the city and county of Philadelphia, State 5 of Pennsylvania, have invented a new and useful Device for Removing Snarls, Kinks, Slacks, &c., from Yarn and Thread, of which the following is a specification.

My invention consists of a device adapted 10 to remove snarls, kinks, slacks, etc. from yarn and thread, as will be hereinafter set forth.

For the purpose of explaining the invention, the accompanying drawing illustrates 15 a satisfactory reduction of the same to practice, but the important instrumentalities thereof may be varied, and so it is to be understood that the invention is not limited to the specific arrangement and organization 20 shown and described.

Figure 1 represents a perspective view of a device for removing snarls, kinks, slacks, etc. from yarn and thread embodying my invention. Fig. 2 represents a side elevation 25 of a portion of the same on an enlarged scale. Fig. 3 represents a vertical section of a portion on an enlarged scale. Fig. 4 represents a partial plan view and partial horizontal section of a detached portion.

Similar letters of reference indicate corresponding parts in the figures.

Referring to the drawing: A designates a plate or member, on which cops or bobbins of yarn or thread are supported. Rising 35 from said plate and firmly secured thereto, is the standard B, on the upper end of which is sustained the head C and spreader D, the latter being disk-shaped formed of a plate having a rounded edge, said plate resting 40 on the former, said end of the standard being threaded for the engagement of the nuts E, E, which are adapted to be screwed respectively against said head and cap and retain the same in firm position on said 45 standard while providing means for adjusting the distance the yarn or thread is to be run off from the cops or bobbins.

Extending laterally from and secured to the head C, are the arms F, whose outer ends 50 are bent angularly forming fingers G, which are in pairs, the outer limb members of which project in opposite directions and are set preferably at an inclination to the vertical direction of said head, it being noticed 55 also that said fingers are located approxi-

mately under the periphery of the spreader D. Such inclination is clearly shown in Fig. 1.

It will be seen that the yarn or thread as drawn from the cops or bobbins is passed 60 around over the bend or angle of one of the fingers of a pair and then under the bend or angle of the other finger of the pair, and so subjected to a double frictional or rubbing action so as to be divested or relieved of 65 snarls, kinks, slacks, and the like.

Owing to the fingers G, the yarn or thread is prevented from outward disengagement from the arms F, while the spreader D prevents the yarn or thread from running inwardly and being carried against the head C and fouling therewith or winding on the same.

When the yarn or thread reaches the spreader, it runs upwardly on the rounded 75 edge of the same with smoothness and little friction and from thence is conducted to a reel for well known purposes.

The fingers G are arranged back to back on the head with their free ends extending outwardly in opposite directions so that the yarn or thread will not disengage itself from the bends of the fingers, the overhanging spreader on the head serving to keep the 80 yarn or thread on the bends of the fingers. 85 The periphery of said spreader is so rounded that as the yarn or thread reaches the same, it passes on its way to a reel, running on said periphery smoothly and with reduced friction and without liability to disengage from said fingers owing to the spreader having its periphery beyond said fingers so that the yarn or thread extends obliquely outwardly from the fingers to the 90 periphery of said spreader, thus keeping the 95 yarn or thread on the bends or angles of the fingers.

The device will be found admirably adapted for "re-doubling" purposes.

It will be noted upon reference to Fig. 3 100 that the spreader D has an outwardly and downwardly extended peripheral flange which is formed upon curved lines and that the yarn or thread contacts with such rounded edge and that there are no yarn guiding eyes on said spreader to draw the thread inward at an angle to said edge, the proper tension being given to the yarn or thread by its passage through the arms F and over the 105 edge of the spreader.

Having thus described my invention, what I claim as new and desire to secure by Letters Patent, is:—

1. In a device of the character stated, a spreader, outwardly extending fingers, and a support for said spreader and fingers, said fingers being independent of each other and of angular form arranged back to back, and said spreader outwardly overhanging said fingers.

2. In a device of the character stated, a cop-support, a standard rising therefrom, a head on said standard, a disk-shaped spreader on said standard above said head

and extended laterally beyond the same, 15 means for adjustment of said head and spreader on said standard, and angular arms each independent of the other, said arms extending laterally from said head beneath said spreader, the outer limbs of said arms 20 extending in opposite directions and inclined from the perpendicular and having their angles adjacent to each other, back to back.

JOHN FRIEND LODGE.
